UNITED STATES PATENT OFFICE.

ARTHUR T. HAGEN AND DANIEL M. COOPER, OF ROCHESTER, NEW YORK.

MANGLE.

SPECIFICATION forming part of Letters Patent No. 451,479, dated May 5, 1891.

Application filed May 28, 1890. Serial No. 353,456. (No model.)

To all whom it may concern:

Be it known that we, ARTHUR T. HAGEN and DANIEL M. COOPER, of the city of Rochester, county of Monroe, and State of New York, have invented certain new and useful Improvements in Mangles; and we do hereby declare the following to be a full, clear, and exact description of the same, reference being had to the accompanying drawings, forming 10 a part of this specification, and to the letters of reference marked thereon.

Our present invention relates to mangles or ironing-machines for ironing sheets, towels, napkins, bed-spreads, &c., and has for its objects to provide a machine simple and cheap in construction, in which the pressure on the articles may be readily controlled, and one in which the articles operated upon may be fed into the machine straight and in position to 15 be properly acted upon by the irons; and to these ends the invention consists in certain novelties of construction and combinations of parts, all as will be hereinafter fully described, and the novel features pointed out 20 in the claims at the end of the specification.

In the drawings, Figure 1 is a side elevation of a machine constructed in accordance with our invention; Fig. 2, a longitudinal sectional view of the same on the line xx ; Fig. 30 3, a top plan view; Fig. 4, a front view; Fig. 5, a detail sectional view of the end of one of the rollers and irons; Fig. 6, a detail side elevation, partly in section, of the feeding-roller.

Similar letters of reference in the several 35 figures indicate similar parts.

The main frame of the machine preferably consists of the two side pieces A A, connected at the front or feed end by brace A' and at the rear by a tie-rod A². Mounted in boxes 40 b b in the side frames A A are the rollers B B' B² B³, (in the present construction four being employed,) said boxes sliding in guides and being normally pressed downward or toward the irons by springs c, the tension of 45 which may be regulated by hand-wheels d. Upon each end of the rollers, which are suitably padded, as usual, are located gear-wheels C C, between which are arranged idler-gears D, mounted on studs secured to the sides of 50 the frame, causing all of said rollers to be rotated in the same direction, the teeth for said wheels being long enough to permit the neces-

sary movement of the rollers without being disengaged.

The main shaft E, journaled in the frame, 55 extends clear across, and at one end is provided with a belt-pulley F, and near the other with a gear G, from which motion is transmitted to the rollers B B' B² B³ by a train of gears G' G² G³ G⁴. The iron for the goods 60 consists of a series of recessed surfaces, in which the rollers partly enter, as shown, so as to give great surface contact, and for convenience in construction we prefer to make this in sections H H' H² H³, having at the ends 65 flanges h, by which they are bolted or otherwise secured to bars J J, constituting a frame pivoted on tie-rod A² at the rear end of the machine and supported at the forward end upon suitable adjusting devices, further described. 70 The top surfaces of the abutting sides of these sections are rounded and fitted together, as shown, so that when they are secured to the bars J a continuous ironing-surface will be formed, and they are also preferably arranged 75 on an incline, as shown, the front roller and iron being highest, so that the goods can readily and naturally pass through the machine and be acted upon by the various rollers in succession without liability of getting out of 80 place or requiring the operator to guide them in a certain definite course. This arrangement serves, also, to bring the feed end at a convenient height for the operators feeding the machine who stand, while those receiving 85 the ironed articles can conveniently sit down and fold or otherwise dispose of them. Any suitable devices can be employed for heating these sections of the iron; but we prefer to connect steam-pipes g to their opposite ends 90 and circulate steam through them.

The forward ends of the bars J are provided with bosses j, entering recesses or sockets in the ends of bars or rods K, which latter are threaded near their lower ends and pass 95 through correspondingly-threaded nuts L, resting on the brace A' of the main frame. Connected to or formed upon these nuts are worm-wheels L', with which engage worms L² on a shaft M, journaled in the frame and adapted to be rotated by a handle or crank M', so that by the rotation of the shaft the front ends of bars J will be elevated or depressed and the pressure between the rolls 100

and iron regulated as desired. A suitable scale *m* is provided on the front of one of the sides of the main frame, with which co-operates an index or pointer *n* on one of the bars *J*, (see Fig. 4,) so that the desired adjustment can readily be had.

The pivotal point (rod *A*²) of the frame, it will be noted, is quite near the center of the rearmost roll *B*³, and said frame moving in the arc of a circle comparatively little variation of the pressure of this roll and its co-operating surface will be had when the frame is adjusted, and this constitutes one advantageous feature of this machine. In ironing one class of goods—such as sheets, towels, and the like—it is desirable that the goods be soft and pliable, and this is caused by gradually drying and ironing them, and with another class of goods it is desirable to have them more or less stiff without being starched, which is caused by drying and ironing them at first with pressure and heat, and the present machine is designed to accomplish this. The pressure between roll *B*³ and its ironing-surface remaining practically constant, by lowering the outer end to the lowest point the pressure between roll *B* and its co-operating surface will be least and gradually increasing in the other rolls up to roll *B*³, thereby first lightly pressing and drying and lastly ironing the articles, and by moving the outer end of the iron up to the highest point the pressure will be greatest between roll *B* and its co-operating surface, and that between roll *B*³ and its co-operating surface will be the least. These adjustments enable the operator to regulate at once the machine to accomplish the results desired, the scale and pointer serving as guides.

Instead of employing two rods *K* at opposite sides of the machine, it is obvious that the bars *J* could be connected at their forward ends and a single adjustable device applied in the center; but we prefer the arrangement shown.

At the feeding end of the machine, which we denominate the "front," is arranged a trough or receptacle *O* for containing the articles to be ironed, having a table or ledge *P*, on which the edges of the articles are spread preparatory to entering them in the machine, and at the rear is located a table or support *X*, on which the articles are received after being ironed.

In machines of this class, where long irons and rollers are employed between which the articles, such as sheets, are passed, great difficulty has been experienced in properly entering both ends, as otherwise one corner or portion might be drawn in in advance of the other, the article pulled through crooked, and wrinkles formed, and oftentimes this would occur through the operative's unwillingness to put her hands close enough to the iron to enter the article properly through fear of an accident. With the idea, therefore, of providing an improved device whereby the operator

may properly position the article without danger to herself and feed it to the machine so that it will be ironed and dried smooth, we provide a roller or equivalent feeding device under her control, which may be brought into contact with and feed the article properly to the pressing devices.

In the present embodiment of our invention this feed-roller *R* is mounted upon arms *Q* *Q*, journaled upon the journals of roll *B* or suitable studs, if desired, and connected with said roller by means of a sprocket-chain *S*, passing over wheels *S'* *S*² on the shafts of said rollers *R* and *B*, respectively, so as to be rotated therefrom. The arms *Q* are connected by rods *t* with a treadle *T*, pivoted on the floor, said rods having adjustable collars *r* thereon, between which and lugs *s* on the frame are arranged springs *v*, which tend to raise the rods and the roller *R* above the support *P*; but the operator can, when desired, move the treadle down and bring said roller down on the article spread upon the support, as will be readily understood. Instead of employing springs to lift the roller, a weight could as well be employed, if desired. It will be noted that the rollers are arranged on an incline, in order that the article being operated upon may readily pass from one iron-section to the next without danger of being wrinkled or improperly received, and upon the rear side of the first roller or subsequent rollers, if desired, is arranged one or more weighted scrapers *V*, pivoted on shaft *W*, adapted to prevent the articles from sticking to the roller and wrapping around it. These scrapers may, if desired, be turned back out of operative position, as shown.

The operation of the parts will now be readily understood. The article to be operated upon—say sheets or other long pieces—are placed in the trough *O*, and the operator then lifts up the edge and arranges it perfectly flat and straight upon ledge *P*, ready for introduction into the machine, and then steps on treadle *T*, bringing feed-roller *R* down upon it and causing it to be carried with its edge straight between roll *B* and its co-operating iron-section, where it will receive its preliminary pressing and drying, then, passing to the next iron-section and co-operating roller, will be again operated upon, and so on until finally delivered at the end of the machine upon table *X*.

It is obvious that instead of mounting the irons on the adjustable frame the rollers, by a simple arrangement, could be made to adjust toward and from the irons, the latter being stationary, and this we regard as the equivalent, broadly, of the arrangement shown, the details of construction being of course modified; but the feature of mounting one of the co-operating parts on a pivotal frame, the adjustable feature described, will be preserved.

By arranging the rollers and iron as described the adjustments can easily be had and

the separate ironing-sections can readily be removed, if necessary or desirable. The whole machine is simple, easily operated, and, as we have found by practical operation, is admirably adapted for the purpose.

5 We claim as our invention—

1. The combination, with a series of rollers, of an ironing-surface co-operating therewith pivoted near one end of the series of rolls and 10 adjusting devices for moving the free end, so as to regulate the pressure, substantially as described.

2. The combination, with a series of rollers mounted in sliding boxes and springs for operating upon them, of an ironing-surface co-operating therewith pivoted near one end of the series of rolls and adjusting devices for moving the free end of the ironing-surface, so as to regulate the pressure, substantially as 25 described.

3. The combination, with a series of rollers, of the bars pivoted at one end, the ironing-surface composed of the series of sections having recessed faces co-operating with the rollers and arranged with their edges abutting, and adjusting devices for moving the free end of the bars to regulate the pressure, substantially as 35 described.

4. The combination, with the series of rollers, 30 of the series of ironing-surfaces with which the rollers co-operate, and the two bars pivoted near one end of the series, on which the ironing-surfaces are supported, the two rods having the threads, the nuts having worm- 35 wheels thereon, and the shaft, with the worms co-operating with the latter, substantially as described.

5. The combination, with an ironing-machine having a table or support at the feed 40 end, of a rotating feeding-roller normally held out of contact with said table, and a lever connected to said roller for bringing it down into contact with the goods on the table to feed

them to the machine, substantially as described.

6. In an ironing-machine having a pressing-roller and having a table or support at the feed end, the combination of a rotating feed-roller, the pivoted arms in which it is mounted, and a lever connected to one of said arms for 50 bringing the roller down into contact with the goods on the table to feed them, substantially as described.

7. In an ironing-machine having a pressing-roller and a support or table in front of it, 55 the combination of the pivoted arms, the feed-roller carried thereby connected to and driven from the pressing-roller, the spring for elevating the arms, and the foot-lever connected to them for bringing the roller into 60 contact with the goods to feed them, substantially as described.

8. In a mangle substantially as described, the combination, with the series of padded pressing-rollers, of the ironing-surface composed of a series of sections having recessed faces co-operating with the rollers and rigidly secured together, with their edges abutting, forming a continuous surface, whereby short articles will follow through the machine from 70 one roller to the next and be thoroughly dried and ironed, as set forth.

9. In a mangle, the combination, with a continuous ironing-surface on which the work rests and over which it passes, comprising a 75 series of depressed portions, of a series of padded pressing-rollers for co-operating with the work in the depressions and feeding it from one to the next, substantially as described.
